UNITED STATES PATENT OFFICE.

WILLIAM C. BANKS, OF NEW YORK, N. Y., ASSIGNOR, BY MESNE ASSIGNMENTS, TO
N-W EQUIPMENT CO., INC., OF NEW YORK, N. Y., A CORPORATION OF NEW YORK.

CONNECTOR.

1,111,782.

Specification of Letters Patent. Patented Sept. 29, 1914.

Application filed July 29, 1913. Serial No. 781,776.

To all whom it may concern:

Be it known that I, WILLIAM C. BANKS, a citizen of the United States, residing in the borough of Bronx, city and State of New York, have invented certain new and useful Improvements in Connectors, (Case A,) of which the following is a specification.

This invention relates to electrical connectors and has reference particularly to a special form of connector whereby connection may be made to the third rail or one of the running rails of an electrical railway system.

In electric railway systems, it is frequently necessary to work on the roadway at night or in dark places, such as tunnels, and to secure illumination for such work it is common to take current from one of the supply wires or the third rail of the system. Heretofore difficulty has been experienced in making the connection to the third rail and the return connection to the running rail, this having been done by twisting the end of a conductor around a bolt employed in connection with the rails or in some other manner of a similar character.

In accordance with the present invention, a connector of special form is provided for effecting connection to a rail, this connector being so constructed that the connection can be quickly effected and so that good electrical contact is made. The connector is so constructed that it may be used with rails varying in size over a substantial range. Furthermore the connector is so constructed as to provide for a fuse whereby the lamps employed are protected against the flow of an abnormally large current.

The preferred embodiment of the invention is illustrated in the accompanying drawings, in which—

Figure 1 is a view of the connector, partly in section and partly in elevation, showing the same attached to a rail, Fig. 2 is a plan view of the connector and rail, the rail and a portion of the connector being in section, Fig. 3 is a detail view of a portion of the connector and Fig. 4 is a section on line 4—4 of Fig. 1.

Referring to these drawings, 5 indicates a rail of an electric railway system, either the third rail supplying current to the sys-

tem or one of the running rails. The connector comprises a body-portion 6 made of metal and shaped to provide an engaging surface 7 adapted to engage the flange of the rail 5 at one side thereof. The body-portion 6 has a member slidably mounted thereon and shaped so as to engage the opposite side of the flange of the rail. This member is here shown in the form of a hook 8 bent to provide an engaging surface 9. The shank of the hook is arranged to slide in openings provided for it in the body-portion 6 of the connector. A spring 10 is coiled about the shank of the hook 8 between one of the parts of the body-portion 6 and a pin 11. Preferably the shank of the hook is provided with a lengthwise slot 70 through which extends a pin 12 on the body-portion 6 so as to prevent turning of the hook in the openings provided for it in the body-portion 6.

The body-portion 6 of the connector has 75 an annular boss 13 formed integral therewith, this boss being exteriorly-threaded as shown in Figs. 1 and 3. A tube of insulating material 14 fits snugly within this boss 13 and extends beyond the same as shown 80 in Fig. 1. A hollow handle 15 is detachably connected to the body-portion 6 of the connector, this handle being provided with a thread upon its interior surface for coaction with the thread on the boss 13. This handle 65 is made of insulating material and because of its connection to the body-portion 6 which supports the hook 8, the connector may be conveniently manipulated by means of this handle. The handle is also arranged to 90 enclose a removable fuse which is connected in circuit when the connector is applied to a rail. For this purpose, the handle 15 is provided with a contact 16 located within the interior of the handle against a transverse 95 interior wall of the handle as shown in Figs. 1 and 2. This contact 16 has a threaded stem 17 integrally connected therewith and threaded to receive a nut 18 by which the end of a conductor 19 is connected to the 100 contact 16. When assembling the parts, the tube 14 of insulating material is placed within the boss 13 and a fuse 20 is inserted within the tube 14. The handle 15 is then applied over these parts and screwed up 105 upon the thread on the boss 13. As the han-

dle is thus tightened up, the contact 16 engages one end of the fuse 20 so as to make electrical connection thereto and presses the other end of the fuse into contact with the body-portion 6 of the connector.

With the parts constructed and assembled in the manner above described, the connector may be quickly applied to a rail and so applied as to make good connection therewith. This is done by applying the engaging surface 9 of the hook 8 to one side of the flange of the rail, pulling on the handle 15 so as to draw the engaging surface 7 from the engaging surface 9 against the tension of spring 10 until the surface 7 may be applied to the other edge of the flange of the rail in the manner shown in Fig. 1 and then relaxing on the pull upon handle 15 so that the two engaging surfaces come together against opposite sides of the flange. Electrical connection is then made from the rail to the hook 8 and body-portion 6, through the fuse 20 to the contact 16 and through the stem 17 to the conductor 19. From this conductor the current passes through the lamps in series to a similar conductor which has a connector like that above described at its end, this connector being adapted to be connected to one of the running rails in the manner above described.

It will be seen that with this conductor good electrical connection may be made to a third rail or a running rail very quickly. Also the connection for supplying current to the lamps is provided with a fuse to protect it and this fuse may be readily removed and replaced when burned out.

Having described my invention, what I

claim as new therein and desire to secure by Letters Patent of the United States is:

1. A connector comprising a metallic body-portion having an engaging surface and an annular, exteriorly-threaded boss, a hook slidably mounted on the body-portion and in electrical contact therewith, a spring acting on the hook and tending to move it toward said surface, a hollow handle of insulating material interiorly-threaded for detachably mounting it on said boss, a contact stationarily mounted within the handle and a fuse inclosed by the handle and engaging said contact and said body-portion, substantially as set forth. 40

2. A connector comprising a metallic body-portion having an engaging surface and an annular, exteriorly-threaded boss, a hook slidably mounted on the body-portion and in electrical contact therewith, a spring acting on the hook and tending to move it toward said surface, a tube of insulating material extending within the boss, a fuse in said tube, a hollow handle of insulating material inclosing said fuse and tube and interiorly-threaded to coact with said thread on the boss and a contact mounted within the handle in position to engage one end of the fuse and force the other end thereof into engagement with the body-portion, substantially as set forth. 45

This specification signed and witnessed 50 this 25 day of July, 1913.

WM. C. BANKS.
